UNITED STATES PATENT OFFICE.

CHARLES UEBELMESSER, OF NEW YORK, N. Y.

STEAM GENERATOR.

Application filed July 22, 1926. Serial No. 124,198.

The object of my invention is to afford simple but effective water heating and boiling means in which the caloric imparted thereto is utilized to a maximum degree for 5 the generating of steam expeditiously and economically,—and to this end the invention consists essentially in the combination and arrangement of elements and devices described and claimed, whereby these and 10 other advantageous results are attained, distinctive features being the positioning of a heating unit medially between superposed primary and secondary tubular water boiling elements through which the gaseous 15 products of combustion are drawn by a draft flue common to both, and the provision of means whereby a continuous automatic water circulation is attained and insured between the said primary and secondary water heating 20 elements, all as hereinafter fully set forth.

In the accompanying drawing, which is a sectional elevation diagrammatical in character, I illustrate a practical embodiment of the essential features of my invention in steam generating apparatus such as designated, although I do not limit myself to the identical construction and arrangement of parts thus shown by way of exemplification, since changes may be made in minor 25 details, and equivalent mechanical expedients resorted to, with like results, and without departing from the spirit and intent of my invention in this respect.

30 With this understanding:—

P, represents a lower primary water heater, and S, an upper secondary boiler and steam generator, B, representing a heating element interposed between them, and consisting of a suitable burner having nozzles both in the top and bottom thereof through which the fuel may pass thereby to cause flames to impinge against the top of the primary water heater P, and against the bottom of the secondary boiler and generator S, as shown, said burner B, being supplied with gas, by a pipe b.

The primary water heating element P, is formed with vertical flue tubes p, for the 35 passage of the products of combustion from the burner B, downward to the lower branch F', of the main exhaust flue F. The burner B extends across substantially the entire space between the water heater P and the generator S and acts as a baffle between the upper and lower flames, which flames are

projected both upwardly and downwardly by the pressure of the fuel to impinge directly against the lower wall of the generator S and the upper wall of the heater P, 40 respectively. In like manner the secondary boiler and steam generating element S, is formed with vertical flue tubes s, s, through which the products of combustion emanating from the burner B, pass upward to the upper branch F², of said main exhaust flue F. Because of the baffling function performed by the burner and also because of the fact that the upper flue tubes s, s, which carry off the combustion gases through the generator 45 S have not sufficient capacity to carry off all of the gases from both the top and bottom flames, and furthermore because the fuel is projected outwardly from the burner under pressure, practically all of the combustion gases from the lower flames will pass 50 downwardly through the lower flue tubes p, p. A drain pipe s' is provided at the lower part of the generator S for permitting the water to be drained therefrom and for cleaning out purposes, said pipe being furnished 55 with a valve or shut off cock s².

Water is supplied to the lower part of the primary water heating element P, by a feed pipe p', controlled by a valve p²; and 60 the upper part of said primary water heating element P, is connected with the lower part of the secondary boiler and steam generative element S, by a coupling pipe c, said steam generative element S, being also connected with the primary heating element P, 65 by means of a return pipe c', extending from the bottom of said secondary heating element S, to approximately the bottom of the primary heating element P, substantially 70 as indicated on the right of the arrangement of parts shown in the drawing, although this identical positioning of the pipes c, c', is not essential, provided they function as intended as means of effecting an automatic and continuous circulation of water 75 between and through both water heating elements as clearly indicated in said drawing.

It is to be noted in this connection that the water as introduced into the bottom of 80 the secondary or steam generating element S, is taken from the top of the primary boiler P, or in other words from the hottest part thereof, so that the water fed to the steam generating element S, is preheated 85 sufficiently to expedite steam generation in the latter, and this result is further promoted 90

by the automatic circulation of water between and through both the heating elements P, and S, whereby my duplex heating system is adapted to the rapid generation 5 of a maximum quantity of steam in a minimum of space and capacity, thereby rendering the same specially useful for steam-driven automobiles and vehicles generally, and for analogous uses where economy of 10 space and fuel combined with prolific steam production is a desideratum.

The operation of the boiler will be as follows: The burner B being lit the downwardly directed flames issuing from the bottom of 15 said burner will impinge directly upon the top of the primary heating element P and, as this element is filled with water, the water in contact with the top thereof will be quickly heated to a high temperature and will immediately pass upwardly through the pipe c 20 to the upper secondary or steam generating element S, to be further heated in the element S by the uppermost flames of the burner. The combustion gases from the 25 lowermost burner flames in passing through the flue tubes p gradually heat the body of water in the element P and as the water at the bottom of said element is quite cool the major part of the heat is extracted from said 30 gases by the time they issue from the bottom of said tubes. After the burner has been in operation but a short time the water in the lower element P is heated sufficiently, both by the flue gases passing through the 35 tubes p and the passage of some of the highly heated water through the pipe c' from the upper element to replace the water which passes upwardly through the pipe c, so that the water at the top of the element P 40 is practically instantaneously heated to the boiling temperature by the heat of the direct flames, there being no lag in the heating effect because of the setting up of convection currents such as are produced when 45 the heat is applied from beneath an element containing water to be heated.

Obviously, an important factor in my system and means for rapid steam generation, is the positioning of the burner B, between 50 the primary heating element P, and the secondary or steam generative element S, in conjunction with the drawing off of the products of combustion through the flues thereof, and discharge of said gases through 55 a main exhaust, as set forth.

I have herein shown and described the heating element B, as consisting of a gas burner as a unit, although other heating means might be substituted therefor, under 60 certain conditions and requirements, with essentially like results, the distinctive feature in this respect being the interposition of a heating element between the superposed sections of a duplex boiler, in which one section is arranged above the other and the

heat from the burner is directed both upwardly to heat the upper section and downwardly upon the top of the lower section which is filled to said top with water.

s, is the steam delivery pipe.

What I claim as my invention and desire to secure by Letters Patent, is:—

1. A steam generator of the character designated, comprising a primary water heating element formed with vertical flues 75 and a superposed secondary water heating and steam generating element also formed with vertical flues and connected with said primary heating element by means which provide for a water circulation between and through both, and a burner interposed therebetween, and adapted to cause flames to impinge against both of said water heating elements, together with means for drawing off the products of combustion downwardly 80 through the flues in said primary element and upwardly through said secondary water heating element, and discharging same through a common exhaust, substantially in 85 the manner and for the purpose set forth. 90

2. In a steam boiler, the combination of a pair of communicating boiler sections arranged in vertically spaced relationship, each of said sections being provided with a plurality of vertically extending flue tubes, and a burner, provided with means to direct flames both upwardly against the upper section and downwardly against the lower section arranged in the space between said sections. 100

3. In a steam boiler, a pair of communicating boiler sections arranged in vertically spaced relationship, each of said sections being provided with a plurality of vertically extending flue tubes, a main flue extending 105 vertically adjacent to said sections, two horizontally extending branch flues in communication with said main flue, one of said branch flues communicating with the flue tubes for the upper section at the top thereof and the 110 other branch flue communicating with the flue tubes for the lower section at the bottom thereof and a burner located in the space between said sections. 115

4. In a steam boiler, the combination of 120 a pair of communicating boiler sections, arranged one above the other with a space between them, a burner located in said space and provided in its upper and lower sides with a plurality of burner nozzles, and flue passages for conducting the combustion gases from said burner downwardly through the lower one of said sections and upwardly through the upper one of said sections. 125

5. The combination in a steam boiler as 130 set forth in claim 4 in which the burner extends substantially entirely across the space between the boiler sections and acts as a baffle to prevent the gases from the lower burner nozzles from ascending.

6. In a steam boiler, the combination of
a pair of boiler sections, arranged one above
the other with a space between them, a
burner located in said space and provided,
5 in its upper and lower sides, with a plural-
ity of burner nozzles, flue passages for con-
ducting the combustion gases from said
burner downwardly through the lower one of
said sections and upwardly through the up-
per one of said sections and conduits connect-
ing said sections for permitting circulation
by convection of the water contents of said
sections. 10

CHARLES UEBELMESSER.
